A. M. SMOLENS

FIGURE TOY

Filed Nov. 27, 1922

FIG. 1.

FIG. 3.

FIG. 4.

FIG. 2.

Inventor
Abraham M. Smolens

By his Attorney
Levitt & Block

UNITED STATES PATENT OFFICE.

ABRAHAM M. SMOLENS, OF NEW YORK, N. Y.

FIGURE TOY.

Application filed November 27, 1922. Serial No. 603,406.

To all whom it may concern:

Be it known that I, ABRAHAM M. SMOLENS, a citizen of the United States of America, residing at New York city, Bronx 5 County, State of New York, have invented certain new and useful Improvements in Figure Toys, of which the following is a specification.

This invention relates to mechanical toys 10 and has for its object the provision of a novel toy of this class appropriate for babies and small children of either sex.

Another object is to produce a toy mechanism adapted to agitate a jointed puppet 15 and requiring the use of one hand only, the old style of flapping jointed figures or "jumping jacks," as they are also called, requiring simultaneous manipulation by both hands in working them.

20 A further object is the provision of a toy by which the muscles of the hand and fingers may be developed without overstraining them.

As a fourth object this mechanical toy 25 like other mechanical toys is intended to be instructive inasmuch as it stimulates the natural inquisitiveness of children concerning cause and effect of actions, they perceive.

30 A fifth object is to devise a mechanism which accomplishes the purposes indicated above by the simplest possible means.

A final object is to make the operating 35 parts of said mechanism of such construction that not only jumping figures can be agitated by it, but any other toy which requires reciprocating rotary movement or may utilize such movement as a substitute for continuous rotation in one direction, as 40 for instance a fan or toy-windmill or twirling star and so forth.

These and similar objects are accomplished by means of such structure and 45 novel arrangement of parts as are herein-after described and shown in the accompanying drawings, which form a part of this disclosure, and which are to be considered as illustrative and descriptive only and not as restrictive or limitative, and in 50 which:

Figure 1 shows an assembly of all the parts of the invention.

Figure 2 is a modification of the operating mechanism, devised on and following 55 the same mechanical principles, the driven puppet being omitted in the illustration.

Figure 3 is a sectional view on the line 3—3 of Fig. 2.

Figure 4 is a top view of the mechanism shown in Fig. 2.

Similar numerals of reference indicate corresponding parts in the several views.

Referring to the drawings in detail, the numeral 10 will be seen to designate the stationary or body part of a flapping figure 60 which may show any desired design and represent any appropriate animated object, for instance a clown.

The legs 11, and the arm 12, linked to the body by means of rivets 13 and 14 respectively, complete the puppet. 70

The whole figure may be either made of flat paste board, on which the design is painted on one or both sides, or be a corporeal manikin having depth as well as 75 width and height.

This figure is mounted in any suitable manner, as indicated by the rivet 15, on a supporting rod 16, the lower end of which is rotatably socketed at 17 in a handle 18. 80

On the rod 16 is fixedly secured a pinion 20, and the pinion being also supported underneath its hub 21 in an axial direction on the handle 18, the latter is appropriately capped at this point with a perforated conical metal bearing 22 to diminish friction, when the pinion is rotated. To give the rod 16 additional guidance a side bracket 24, partly shown dotted, is attached to the flattened upper side of the handle 18, said 90 bracket consisting of a flat band where top end 25 is bent over at right angles and perforated to embrace the rod 16 above the fixed pinion 20.

The upper part of the handle 18, is flattened on both sides, as indicated by the plane surface 26, located diametrically opposite the flat band 24, so as to fit, together with the latter into the parallel legs of a U-shaped band clip 27 which is rigidly fastened to both of them by means of the rivet 28. 95

Through the protruding ends of the clip a pin 29 is drawn at right angles to the handle, with both ends riveted over, and this pin serves as a fulcrum for the double-armed lever 30, made of a flat band, rolled into a channel-shaped section, as Fig. 4 more clearly indicates, and bent at the fulcrum at an obtuse angle, bell-crank fashion. The 105 upwardly directed arm 30^a in a normal position runs approximately parallel to the

handle, while the downwardly inclined arm 30^b, diverging from the handle, is fitted at the end with another handle 31.

Around the pin, inside the channel-shaped hollow of the lever 30 is wound a loop spring 32, whose straight ends 32^a and 32^b rest in the hollow of the lever and a slot 33, provided for this purpose in the handle 18, respectively.

10 Thus the two handles, the lever 30 and the spring form a pair of resilient tongs.

To the upper extremity of the lever arm 30^a is rigidly fastened by a rivet or otherwise a rack 34 which the pinion 20 permanently engages. This rack may be formed in various suitable ways, the main condition being that it forms a circular segment with the pivotal point 28 as a center. As a preferred form it is proposed to be made out of 20 a flat strip of metal, lying in the swinging plane, except for the curled-over end 35, by which it is fastened to the lever, and perforated by a series of openings or oblong slots 36 matching with the teeth of the pinion.

25 The mode of operation is obvious from this foregoing description. By alternately compressing and releasing the handles of the tongs the segment 34 imparts a reciprocating rotary motion to the pinion. This being rigidly attached to the rod 16, revolves the latter together with the figure, fixed to its top, and the centrifugal force, thus imparted to the jointed members of 30 said figure, spreads them apart, while the interruption, caused by the reversal of the rotary motion, causes said members to temporarily drop again.

35 The modification of the mechanical or operating parts, shown in Figs. 2 to 4 differs from the original and preferred arrangement in that the lever 30, together with the rack 34 and the handle 31, is doubled and assembled in cooperating, opposedly ar-

40 ranged pairs, as indicated by the corresponding numerals, with the letters R and L attached as suffixes. The spring 32' in this case is wound around the common pin 29' and rests with its free arms 32'^a and 32'^b in the hollow channels of both levers. The 45 fulcrum portions of the levers, 30^{R'} and 30^{L'} must straddle or overlap each other, as indicated in Figs. 2 and 3.

50 This arrangement dispenses with the former stationary handle 18, the U-clip 27 and the side bracket 24, while the rod 16', which carries the pinion 20', rests in a special eye-socket 37, provided and supported by the eye-shaped lower end on the pin 29'. The pinion in this case engages simultaneously and at diametrically opposite 55 points the two racks 34^R and 34^L.

55 The operation of the assembled toy is identical with the one described above.

Having thus described my invention, 60 what I claim as novel and desire to protect by Letters Patent is:

65 1. A mechanical toy, comprising a puppet with jointed limbs, a shaft on which the puppet is mounted, a pinion, fixedly supported on the shaft, a pair of resiliently connected tongs, cooperating with and rotatably supporting said shaft and a rack rigidly attached to one of the tong tops and adapted to operatively engage said pinion.

70 2. A mechanical toy, comprising a puppet with jointed limbs, a shaft on which the puppet is mounted, a pinion, fixedly supported on the shaft, a pair of resiliently 75 connected tongs, cooperating with and rotatably supporting said shaft and two racks, each rigidly attached to one of the tong tops and engaging the pinion on diametrically opposite sides for imparting reciprocating rotary motion to said pinion.

85 ABRAHAM M. SMOLENS.
